RALPH V. GRAYSON, OF MACON, AND CLAUD M. FOSTER, OF ATLANTA, GEORGIA, AS
SIGNORS OF FORTY ONE-HUNDREDTHS TO POLAR PRODUCTS, INC., A CORPORATION
OF GEORGIA

REFRIGERATION SYSTEM

Application filed April 9, 1930. Serial No. 442,884.

This invention relates to refrigeration systems and applies particularly to the quick freezing of bodies or masses such as food-stuffs. The invention concerns itself with 5 the chilling of air to low temperature by passing it rapidly in closed circulation into heat exchanging relationship to the evaporation element of the refrigerating system of the Carnot cycle type.

10 One of the objects of the invention is to provide a system as above described, in which a plurality of tunnels for receiving the product to be frozen are intercalated in parallel relation in the closed air circulation system, 15 and controlled in such a manner that one or more of said tunnels may be closed to the passage of chilled air, for the purpose of admitting or removing the articles to be frozen without wasting the cold air.

20 Another object of the invention is the provision of tunnels arranged in multiple as above described and thermostatically controlled according to the temperature individual to the tunnels, for closing the respective tunnel or tunnels to the circulation of frigid air upon the attainment in said tunnel or tunnels of a desired freezing point, thus diverting the air current and concentrating its freezing effect upon the tunnels which 30 have not yet reached the freezing point, and therefore remain open to the freezing point of cold air.

Another object of the invention is the provision of a battery of tunnels functioning singly or in multiple as part of the conduit which defines the closed circulation of the refrigerative air, said tunnels normally opening at their ends into a common air flue, also forming part of the circulation conduit, each 40 tunnel having telescopic extensions adapted to be simultaneously advanced into said flues and to abut against the end walls thereof so as to act as valves for isolating the tunnels singly or in plurality from participation in the closed air circulation.

Still another object of the invention is the provision of open ended telescopic extensions for the tunnels, which when in position of abutment against the confronting walls of 50 the flues, as above described, align with doors

in said walls, giving access to the common chamber formed by said tunnels and extensions, for introducing the objects to be frozen at one end and removing them at the other end, while the tunnel being served is isolated 55 from the closed circulation system of air.

A still further object of the invention is the combination, in a closed circulation system of the type described of a tier of trays, adapted to be disposed in the air current and 60 so constructed and arranged as to divert a portion of the air and deflect and circulate it about the objects on the trays, which are to be frozen.

Other objects of the invention will appear 65 as the following description of a practical and preferred embodiment of the invention proceeds.

In the drawings in which the same characters of reference are used through the entire 70 specification to denote similar parts:

Figure 1 is a longitudinal vertical section through a system embodying the present invention, an intermediate part being broken away; 75

Figure 2 is a horizontal section, part being broken away;

Figure 3 is an end elevation, part being broken away and shown in section, this section being taken along the line 3-3 of Figure 2; 80

Figure 4 is a perspective of the sleeve or telescopic extension;

Figure 5 is a longitudinal section on a larger scale, showing the sleeve and its operating appurtenances at one end of the tunnel, the sleeve being shown in closed position, the section being taken along the line 5-5 of Figure 3; 85

Figure 6 is a cross section taken along the line 6-6 of Figure 5, indicating operating means for the sleeve;

Figure 7 is a cross section through a tunnel door along the line 7-7 of Figure 5;

Figure 8 is a view partly in section taken along the line 8-8 of Figure 5, showing the sleeve operating mechanism; 95

Figure 9 is a diagrammatic view showing the electrical connections by means of which the sleeve is effected and controlled; 100

Figure 10 is a plan view of one of the trays a corner thereof being broken away showing a portion of the under-lying tray;

Figure 11 is a side elevation of superposed trays;

Figures 12 and 13 are vertical elevations, partly in section showing door latching mechanism; and

Figure 14 is a diametrical section through one of the door openings showing a door as it appears in closed position.

Referring now in detail to the several figures, the numeral 1 represents a double walled compartment or chamber, the space between the walls of which is preferably filled with insulation material such as cork. This compartment or chamber is divided roughly into two parts, the lower part of which is occupied by a plurality of tiers of tunnels, each of which is designated by the reference character 2. That part of the chamber above the tunnels is left vacant except for the presence of a blower 3 preferably of the centrifugal type, and at least, the evaporation element 4 of a refrigeration system of the Carnot type. This space as shown in Figure 1, also contains the usual other elements of a Carnot refrigerating cycle system, although the showing of these is purely diagrammatic, and they may be located elsewhere without affecting the scope of the invention.

Referring to Figures 1 and 2, it will be noted that the tunnels 2 normally terminate at their ends in planes which are spaced from the front and rear walls of the chamber or compartment, the spaces between said tunnels and said walls affording flues or conduits for the passage of refrigerated air. The tunnels themselves form part of this conduit.

It will be noted from Figure 1 that the air follows an endless path, being drawn by the blower through the evaporation unit of the refrigerating system and then forced into the flue 5 at the left of Figure 1, the air passing through the tunnels 2, emerging into the flue 6 and being carried again through the evaporation element. By means of this recurrent circulation system, a very low temperature of the air may be obtained depending of course, upon the efficiency of the Carnot refrigeration system and the particular refrigerant used therein. In the present instance, it is assumed that carbon dioxide is used as a refrigerant.

The tunnels 2 are arranged in multiple as part of the circulation conduit, that is to say, the said tunnels are normally open at both ends and the air current divides itself when it reaches the advance ends of said tunnels passing equally through each of the tunnels.

The tunnels 2 are so controlled that any one or more of them may be closed at a time, and it is obvious that when this happens, the entire volume of circulating air must pass through the tunnels which remain open,

thus concentrating the refrigerating effect upon these tunnels. The preferred construction of the tunnels is as follows:

The tunnels are formed preferably as rectangular conduits each having a series of rollers 9 journaled therein, adjacent the floor of the tunnel, said rollers affording anti-friction means for advancing the trays which are fed in at the front or advance ends of the tunnels.

The tunnels are likewise formed with extensions at each end in the form of rectangular sleeves 11 such as are shown in Figure 4, said extensions telescoping over the respective ends of the tunnels and being carried by anti-friction bearings 12. When the sleeves are extended, they abut against the respective end walls, of the chamber or compartment. The sleeves thus act as valves and when they are in abutment against the front and rear walls the tunnel or tunnels associated therewith are for the time isolated from the rest of the circulation system.

It is noted in Figure 4 that the sleeves 11 are open at both ends and Figure 1 shows that a door 13 is in alignment with each sleeve so that when the sleeves are in position to close the tunnel, articles to be frozen may be fed into the tunnel through the open ended sleeve merely by removing the door 13 in the end wall of the compartment.

The sleeves are operated manually or thermostatically, and it is preferred that they be so operated as to simultaneously open or close the ends of the tunnels. Operating means for the sleeves is shown in Figs. 5, 6, 7, 8 and 9 and it will be noted that beneath each sleeve is a pair of spaced racks 16 in mesh with gears 17, the latter being carried on a stub shaft 18, which also carries a worm wheel 19 meshing with a worm 20 suitably carried by operating rod or shaft 21. When the shaft is rotated in one direction, the worm rotates the worm wheel which in turn rotates the gear 17, and they in turn operate the racks 16 in one direction. When the direction of rotation of the shaft 21 is reversed, the direction of travel of the gears is reversed and the racks 16 travel in the opposite direction. Thus the sleeve 11 is brought into and out of abutting relation to the end wall of the flues 5 or 6 as the case may be.

It is preferred to operate the tunnels automatically responsive to the temperature conditions in the individual tunnels. By this mode of operation, when a predetermined low freezing temperature has been attained in one tunnel it automatically isolates that tunnel from the general circulation system of chilled air thus concentrating the freezing effect of the entire air column upon the tunnels remaining open. In this manner all of the tunnels are quickly brought to the same desired condition of low temperature.

In carrying out of this automatic phase of our invention, it is preferred to locate in

each tunnel, a thermally responsive device such as a bulb 22, of known construction, containing for instance, an expansible fluid which actuates a diaphragm switch 23. It is to be understood that these specific instrumentalities are merely exemplary and that any form of thermostatic control is within the purview of the invention.

The diaphragm switch closes one or the other of two circuits according to the direction in which the diaphragm is flexed, each circuit including a solenoid 24 or 25 respectively arranged in operative relation to gears 26 and 27 slidably mounted upon a shaft 28 continuously rotated through an electric motor 29. The gears normally have a neutral position determined for them by the springs 30 and 31, but when either of the gears is attracted by the solenoid, it goes into mesh with a ring gear 32 at the end of the shaft 21.

Thus the direction of rotation of the shaft 21 depends upon which of the two gears is in mesh with the ring gear 32. In one instance, the shaft 21 rotates to close the sleeves and in the other case, the sleeves being already closed, the shaft 21 rotates in a direction to open them.

Figure 6 shows that the shaft 21 has two worms 20 and 33, the helices of said worms being arranged in an opposite direction so as to actuate in a reverse manner the gears 34 and 35 which operate the sleeves at the opposite end of the tunnel. It will be understood therefore, that both sleeves move simultaneously to closing position or to open position.

It is of course, obvious that when the sleeves have come into position of abutment with the end walls of the chamber or compartment, it is essential that means be provided to deenergize the solenoids so as to quickly restore whichever of the gears may be in mesh with the ring gear 32, to neutral position. This is provided for in the present invention by contact switches 36 and 37 disposed at opposite ends of the range of travel of the sleeve and adapted to be contacted by the sleeve in either of its extreme positions. The contact switches each comprise contacts 38 and 39 normally kept closed by means of a spring 40, but capable of being opened when one of the contacts is engaged by the adjacent end of the sleeve.

It will be observed from the circuit diagram shown in Figure 9 that the solenoid circuits each include two gaps, one afforded by the diaphragm switch 23 and the other by the contact switch 36, and that the gap at the contact switch 36 is normally closed. Thus when the diaphragm switch moves to close its gap in one or the other direction, the gap at the contact switch is already closed and the circuit is therefore, completed and the solenoid energized, but when the sleeve reaches its limit of movement in one or the other directions, it engages the adjacent contact

switch, opening the same and thus provides a gap in the solenoid circuit, even though the diaphragm switch remains closed. Thus the solenoid circuit will be opened and the gears be permitted to spring to neutral position. It is to be understood that the diagram in Figure 9 suggests that the current for the solenoid circuit be tapped from the power line. The use of a transformer in the solenoid circuit for stepping down the voltage would of course, not amount to invention, being old practice.

It is noted from Figure 5 that the tunnels are double-walled and that except for the reservation of the space for the necessary movement of the sleeves and their actuating mechanism, the jackets afforded by the double walls are lagged with cork or other suitable insulating material.

The products to be frozen are introduced through openings 41 in one of the end walls of the compartment, the said openings being closed by doors 42. When it is desired to charge any one or more of the tunnels with the material to be frozen, the shaft 21 may be manually operated so as to bring the sleeves simultaneously into position of abutment with respect to the end walls of the compartment 1. This manual actuation may be provided by means such as the bevel gear 44, having a polygonal boss 45 adapted to be engaged by a hand crank. When the sleeves have been moved to closed position, the door 42 is opened, the tunnel being at this time isolated from the general circulation of refrigerating air, and the common chamber formed by the tunnel and its extended sleeves, provides a continuous passage into which the articles to be frozen may be introduced and advanced along the bed of rollers 9.

The doors 42 are preferably closed with a sealing fit, the doors being provided by means such as the crank 47 which reacts against hooks 48 diametrically placed with respect to the door, when the handle 49 is moved to the closing position shown in Figure 12.

A wear piece 50 bears against the door and acts as a fulcrum for the crank 47. The materials to be frozen are preferably introduced into the tunnels on trays which may be of any desired construction, but the present invention contemplates the use of a specific tray which used singly or in tiers, provides a new and combinative result in cooperation with the tunnels 2. One of these trays is shown at 50 in Figure 10 and is here formed with partitions 51 dividing it into small article containing compartments. The tray is preferably of wire construction so that the article compartments are open one to the other. At one side of the tray is a series of baffles 52 inclined in such manner when the tray is introduced into the closed air circulation the baffles divert a portion of the air current 120

causing it to flow inwardly upon the articles to be frozen. The trays are preferably formed with baffles on one side only, and the baffles of one tray extending in the opposite direction to the baffles of another tray. The trays are arranged in tiers alternately with the baffles on opposite sides. Figure 10 has the corner broken away to show an underlying tray 53.

It will be noted that while the baffles of the tray 52 tend to entrain and divert a portion of the refrigerating air, the baffles of the under-lying tray are directed rearwardly with respect to the direction of the air current so that the said air current has a suction effect upon said baffles. The aggregate result of the two sets of baffles is that the air is drawn in to one tray, passes around the articles on that tray and then downwardly through said tray on the articles of the next tray from which it is drawn out by the baffles of the under-lying tray.

The trays may be stacked to any desired height, according to the amount of material to be frozen and the height dimension of the tunnel. It is noted that the bank of rollers 9 extending through the tunnels, are inclined slightly downwardly to the discharge end of the tunnels, thus facilitating the feeding of trays continuously into said tunnels by pushing one tray against another, the resistance to movement, of the trays already within the tunnel being diminished by gravity.

Since the doors 42 may be of massive construction, we have indicated a pulley and tongs 58 which may be engaged with said doors for removing them or restoring them to position. This however, is a detail immaterial to the scope of the invention.

While we have in the above description defined what we believe to be a preferred and practical embodiment of our invention, it is to be understood that the details of construction are simply by way of example and not to be considered limitative in their bearing upon the broader phases of the invention.

What we claim:

1. Refrigeration system comprising a continuous conduit for the closed circulation of refrigerative air, including a refrigerating unit for chilling the air, a plurality of horizontal tunnels arranged in parallel in said system with their ends communicating with vertical limbs of said system, and a blower for forcing refrigerated air through said tunnels.

2. Refrigeration system comprising a continuous conduit for the closed circulation of refrigerative air, including a refrigerating unit, a plurality of horizontal tunnels arranged in parallel in said system with their ends communicating with vertical limbs of said system, a blower for forcing said refrigerated air through said tunnels, and selectively operable means for excluding any tun-

nel or tunnels from said circulation system.

3. Refrigeration system comprising a continuous conduit for the closed circulation of refrigerative air, including a refrigerating unit, a plurality of substantially horizontal tunnels arranged in parallel in said system with their ends communicating with vertical conduits, doors in the outer walls of said conduits, a blower for forcing refrigerated air through said tunnels, and selectively operable means for excluding any tunnel or tunnels at both ends from said circulation system, and placing the ends of said excluded tunnels in communication with the outside of said system by way of said doors.

4. Refrigeration system comprising a continuous conduit for the closed circulation of refrigerative air, including a refrigerating unit, a plurality of horizontal tunnels arranged in parallel in said system with their ends communicating with vertical limbs of said system, a blower for forcing refrigerated air through said tunnels, and selectively operable means for excluding any tunnel or tunnels at both ends from said circulation system, said means including open ended sleeves forming part of said tunnels.

5. Refrigeration system comprising a continuous conduit for the closed circulation of refrigerative air, including a refrigerating unit, a plurality of tunnels arranged in parallel in said system, a blower for forcing refrigerated air through said tunnels, and selectively operable means for excluding any tunnel or tunnels at both ends from said circulation system, said means including open ended sleeves forming part of the conduit within said tunnels, the latter communicating with said system by means of ports positioned to be occluded by said sleeves.

6. Refrigeration system comprising a continuous conduit for the closed circulation of refrigerative air, including a refrigerating unit, a plurality of horizontal tunnels arranged in parallel in said system with their ends communicating with vertical limbs of said system, a blower for forcing refrigerated air through said tunnels, and thermally responsive means selectively operable according to temperature conditions in said tunnels for excluding any tunnel or tunnels from said circulation system and thereby diverting an increased proportion of the refrigerative flow through the tunnels remaining open.

7. In a refrigeration system, a tunnel having opposite open ends confronting flues forming part of a recurrent cold air circulation system, open ended extensions at opposite ends of said tunnels and telescopic with respect thereto, advanceable into positions of abutment with respect to the far sides of said flues, means for so advancing said extensions to isolate said tunnel from said

flues, and doors in the far sides of said flues in the areas circumscribed by the abutting ends of said extensions.

8. In a refrigeration system, a tunnel forming part of a closed conduit determining the path of recurrent circulation of cold air, means for producing a circulation of cold air in said conduit, and a tray stack in said conduit having baffles at opposite sides 10 directed respectivley for and aft relative to said air current, whereby air is inducted into said tray stack by one set of baffles and educted by the suction effect of the other set.

9. A tray stack for diverting cold air from 15 a cold air current into intimate cooling relation to the contents of said tray stack, comprising open bottomed trays each having inclined baffles on one side, said trays being arranged alternately with their baffles at opposite 20 sides so that the baffles at opposite sides of the stack open respectively fore and aft relative to air current, whereby air is inducted into said stack by one set of baffles and educted by the suction effect of the other 25 set of baffles.

10. The method of inducting cold air from a cold air current and bringing it into intimate cooling relation to objects on a plurality of similar open bottomed trays having 30 inclined baffles on one side only, comprising: stacking the trays alternately with the baffles at opposite sides and positioning the stack in the air current so that cold air is inducted into one tray by baffles on one side of the 35 stack, passes to the next lower tray, and is educted by the suction effect of the baffles in the opposite side.

In testimony whereof we affix our signatures.
